RELAY CONSTRUCTION

Edward G. Baker, Chicago, Ill., assignor to
 Guardian Electric Manufacturing Co., Chicago,
 Ill., a corporation of Illinois

Application October 13, 1941, Serial No. 414,853

2 Claims. (Cl. 175—336)

This invention relates to a conventional type of electromagnetic relay including a coil and a core, a field piece having an upright leg member disposed adjacent the coil, and an armature hingedly connected to the upper portion of the leg member, in registration with the end of the core.

It has long been recognized as a desirable characteristic of relay construction that the armature be caused to seat flat upon the end of the core, especially when alternating current is utilized, so as to eliminate hum and chatter. Such seating of the armature on the core is also desired when direct current is employed and the relay is constructed to produce a "time delay" operation of the armature. If the armature is not seated flat upon the end of the core for such time delay operation, it will not be possible to obtain the maximum period of timing action. It has also been observed that when switches are mounted entirely upon the field piece, or upon the field piece together with the armature, for control by actuation of the armature, it is of utmost importance to maintain a relatively fixed relationship between the field piece and the core in order to insure maintenance of proper adjustment of the gap or spacing of the cooperating switch elements.

Moreover, it has been found that the leg member of the field piece frequently becomes slightly out of adjustment with respect to the axis of the core. This condition takes place frequently during initial adjustment of the elements, or in handling, or due to the mounting of the relay, as well as incident to and resulting from substantial operation of the armature. Such out of position of the leg of the field piece relatively to the core, usually results in causing the armature to be improperly positioned so as to prevent its being seated flat upon the end of the core. In cases where switch devices are employed and operated by the actuation of the armature, the spacing or gaps of the switch element become altered so as to impair the timing operation of a circuit controlled by the switch devices.

One of the objects of this invention is to provide an improved relay construction which insures maintaining the leg member or members of the field piece in relatively fixed relation to the axis of the core and thereby obviates the foregoing difficulties and undesirable conditions.

Another object is to provide an improved relay structure of the character indicated, characterized by the provision of a panel of non-magnetic material formed with openings for a snug, tele-

scopic fit upon the upper ends of the core and leg member of the field piece.

A further object is to provide an improved relay construction characterized by the provision of a panel of non-magnetic material adapted to be fixedly secured upon the upper end of the coil and connected to the upright leg of the field piece for maintaining the leg of the field piece in substantially fixed relation relatively to the axis of the core.

Other objects and advantages of this invention will be apparent from the following description, taken in connection with the accompanying drawing in which:

15 Figure 1 is a view in side elevation of a relay device constructed in accordance with the present invention;

Figure 2 is an end elevational view of the relay structure;

20 Figure 3 is a horizontal sectional view through the relay taken substantially as indicated at line 3—3 on Figure 1, and

Figure 4 is a detail perspective view of a panel of non-magnetic material utilized in connection with the present invention.

For the purpose of illustration, I have shown in the drawing a form of relay construction wherein the field piece is of generally U-shaped formation, including a pair of spaced apart upright legs and wherein a multiplicity of copper slugs is employed for effecting time delay actuation of the armature when the coil is energized by direct current. In the construction illustrated I have also shown a pair of switches carried on an extension of one leg of the field piece and mounted for control by actuation of the armature. It is to be understood, however, that the present invention is readily adaptable to various types of relays for use either with alternating or direct current, or wherein the field piece is formed with one or two upright leg members disposed adjacent the coil, or wherein switch elements may be added as auxiliary structure to either leg of the field piece or partially on one leg of the field piece and partially on the armature per se, or wherein time delay structure is either present or omitted. It is therefore to be understood that the type of relay shown in the drawing is illustrative of my invention.

50 Referring now in detail to the drawing, the relay structure disclosed is for direct current operation and includes a field piece 10 of generally U-shaped formation including a pair of upright leg members 11 and 12 disposed on diametrically opposite sides of and in straddling

relation to a coil indicated at 14. Mounted centrally within the coil in upright relation is a core, as indicated at 15, the upper end of which protrudes slightly above the upper end of the coil. Mounted below the coil and within the field piece 10 are a plurality of copper slugs 17, the purpose of which is to provide time delay in operation of the armature. Hingedly mounted on the upper end of the leg member 12 of the field piece is an armature 20, extending over and above the coil in registration with the upper end of the core 15. The upper end of the leg member 12 is provided with an extension 12^a which, after assembly of the various parts of the relay, is bent over in the position seen in Figure 1 of the drawing so as to serve as a stop for limiting the extent of upward movement of the armature relatively to the upper end of the core 15. The armature is normally urged in an upward direction against the end of the stop 12^a of the field piece 12 by a coil spring 22 connected to the rear end of the armature at one end, and at the opposite end of a lug extension 12^b formed from the leg 12 of the field piece, as seen in the drawing.

Rigidly attached to the upper portion of the leg 12 of the field piece is a bracket member 25, including a horizontally extending shelf portion 26 extending rearwardly from the field piece and providing a mounting table for one or more stacks of switch devices, as indicated generally at A. In the switch stack shown in Figure 1, there are included two switch devices, one composed of switch fingers 29 and 30, and the mounting ends of said fingers are insulated from each other in the usual manner. The respective co-operating switch fingers of the switch devices are provided with cooperating contact buttons, as indicated at 27^a, 28^a, 29^a and 30^a. The switch fingers 28 and 30 of the two switch devices are slightly longer than their cooperating switch fingers 27 and 29 and extend through horizontally disposed slots 32 and 34, respectively, formed in an upwardly disposed panel 36 of insulating material. Said panel 36 is rigidly secured at its lower end by riveting, as indicated at 37, to an upturned extension 20^a formed at the outer or free end of the armature 20, as seen in Figure 1 of the drawing. It will therefore be apparent that when the armature 20 is attracted to the core 15 the switch members 28 and 30 are drawn downwardly to cause their contact buttons to engage the cooperating contact buttons of the switch members 27 and 29, respectively, for closing the electrical circuits controlled by the respective switch devices. Obviously, the switch fingers may be arranged to be in a normally closed position and caused to be separated by actuation of the armature.

The novel improvement in relay structures and embodying the present invention consists in the provision of a panel 40 of non-magnetic material, preferably insulating material, but it may be any other suitable material of non-conductive characteristic, such as brass, rubber, etc., for maintaining the upright leg or legs of a field piece in fixed relation to the axis of the core. The panel 40 is provided at opposite ends with openings, as indicated at 41 and 42, of a shape and size to insure a snug, telescopic fit upon the upper ends of the leg members 11 and 12 of the field piece. The panel is also provided with a

central opening 43 for a snug, telescopic fit around the upper end of the core 15. It is to be understood that this panel is telescoped over the legs of the field piece before the extension portion 12^a is folded downwardly to constitute the armature stop, as seen in Figure 1.

Desirably, the upper end of the core 15 is upset in any suitable manner, and, as shown in Figure 3 of the drawing, at four circumferentially spaced apart points it is deformed, as indicated at 45, so as to serve to firmly and positively secure the panel 40 in position upon the top of the coil and thereby insure maintaining the leg members 11 and 12 in relatively fixed relation with respect to the axis of the core of the coil, and thereby insure maintaining the armature in position to insure seating flatly upon the entire upper end of the core 15.

Although I have shown and described one embodiment of my invention, manifestly it is capable of modification and re-arrangement without departing from the spirit and scope thereof. It is understood, of course, that the use of a panel in the manner above described, and as disclosed in the drawing, may be modified for adaptation of the invention to a relay structure including a single upright leg on the field piece, in which instance said single leg will be maintained in substantially fixed relation to the axis of the core at all times in a similar manner and with the same attendant advantages. I do not, therefore, wish to be understood as limiting this invention to the precise form herein shown and described, except as I may be so limited by the appended claims.

I claim:

1. In an electromagnetic relay, the combination of a coil having an upright core, a field piece including an upright leg member disposed adjacent the coil, an armature hingedly connected at one end to said leg member, in registration with the end of the core, and means for maintaining said leg member in fixed relation to the axis of the core, for insuring seating of the armature flatly upon the end of said core when the coil is energized, said means comprising a panel of non-magnetic material formed with openings for a snug telescopic fit over the upper ends of said leg member and the core and seated upon the upper end of the coil, said upper end of the core being deformed to permanently and fixedly secure said panel in position.

2. In an electromagnetic relay, the combination of a coil having an upright core, a field piece of generally U-shape formation, including a pair of upright leg members disposed on opposite sides of the coil, an armature hingedly connected at one end to one of the leg members, in registration with the upper end of the core, and means for maintaining said leg members in fixed relation to the axis of the core for insuring seating of the armature flatly upon the end of said core when the coil is energized, said means comprising a panel of non-magnetic material formed with openings for a snug telescopic fit over the upper ends of said leg members and said core, said panel being seated upon the upper end of the coil and the upper end of the core being deformed to permanently and fixedly secure said panel in position.
